11 Claims. (Cl. 229—52)

2

This invention appertains to receptacles or baskets formed of corrugated fibreboard, solid fibreboard or other suitable material and more particularly to a collapsible carrying device in combination therewith.

There are many types of collapsible carrying devices for receptacles and baskets in use at the present time. However, there is a need for an automatically collapsing carrying device in combination with a receptacle wherein the material of the receptacle body is utilized to the fullest extent without sacrificing strength characteristics or complicating the design. When the body material of the receptacle is employed as part of the carrying device, a serious sacrifice of strength usually results. A modern, commercially practical carrier should have an automatically collapsing carrying device so substantial saving in storage space may be realized when the receptacles are stacked vertically one on another. The combination of carrying device and receptacle should also be easy to manufacture and should be adapted for shipment in a "knocked down" condition. It should also be easy for the user to assemble and the carrying device should collapse without injuring the articles carried. The combined carrying device and receptacle to be commercially successful should also provide a maximum unobstructed area for the display of the user's advertising. The present collapsible carrying device and receptacle fully meets all of the requirements set out above.

One of the principal objects of our invention is to provide, in a receptacle of the above noted character, a collapsible carrying device of sufficient strength to support the contents of the attached receptacle, and wherein the device is automatically collapsible to attain a folded, non-projecting position when any downward force is exerted thereon.

A further object of this invention is to provide a collapsible carrying device for a receptacle which will automatically open to a normal carrying position when grasped and lifted by the hand.

A still further object of this invention is to provide a carrying device for a basket or container which uses a minimum of material and utilizes the material already in the receptacle to the greatest advantage.

Another object of this invention is to provide a collapsible carrying device which is simple to operate and simple as well as economical to manufacture. It is likewise an object of this invention to provide a collapsible carrying de-

vice and receptacle that may be shipped in a "knocked down" condition and which requires no tools of any description to set it up in a usable condition.

5 A further object of this invention is to provide a collapsible carrying device and receptacle pleasing to the eye and affording ample unobstructed space for advertising matter.

Other objects and advantages of this invention 10 will be apparent to those skilled in the art upon a full and complete understanding of the construction and operation of the device.

This invention comprises the combination of a 15 carrying device and receptacle wherein the carrying device includes a receptacle handle collapsibly supported in pivoting, sliding and interlocking engagement with flaps foldably connected to the walls of the said receptacle.

The invention also consists in the parts, 20 arrangements and the combinations of parts hereinafter described and claimed. The accompanying drawings form a part of this specification and similar reference numerals therein refer to like parts, wherever they occur.

25 Fig. 1 is an isometric view of the container or basket with the handle shown detached for purposes of revealing details thereof.

Fig. 2 is a transverse sectional elevation of the 30 container with the handle shown in the extended or carrying position, the view being taken at line 2—2 in Fig. 1.

Fig. 3 is a view similar to that in Fig. 2, but wherein the handle is shown in the collapsed position.

35 Fig. 4 is a plan view of the blank or unfolded form of the container comprising the body and handle supporting flaps, and wherein scored portions are indicated by dotted lines and cut edges and slotted portions are indicated by solid lines.

40 Fig. 5 is an enlarged and fragmentary plan view of the flap and handle structure shown in an intermediate position relative to those of Figs. 2 and 3.

45 Fig. 6 is an isometric and fragmentary view of the handle member, showing the manner of engaging the same in a flap opening.

Fig. 7 is a plan view of a modified guide opening in the handle flap, the view being a fragmentary enlargement of one of the container flaps.

50 Fig. 8 is an isometric view of a modified form of a container in combination with the subject handle and supporting flaps, the handle being shown in the open or carrying position.

Fig. 9 is a perspective view of an alternative embodiment of the handle member in which two guide flap notches are provided.

Figures 1 through 4 disclose a preferred form of the container or basket, wherein the main body thereof is prepared in flat, blank form from suitable sheet material. The respective side walls or panels 1 are provided with inner side panels 3 which are folded along the double scores 2 thereby forming the upper edge of side walls 1. The inner panels 3 act as holding members for the end wall flaps 5 when the blank is erected in the usual manner. Each inner panel 3 is die cut or suitably slit to form the respective flaps 4 for the engagement by a handle, as will appear. The supporting flaps 4 are foldably connected to the upper edge of the side walls 1 at the zone of the single scores 6. The outline of the flaps 4 may be of any suitable shape, but a preferred shape with rounded ends and tapering sides is indicated in Fig. 4.

One of the flaps 4 is designated as a pivot flap and is provided with a die cut triangulated opening 7 in which the legs are longer than the base 9 and come together at the apex 8 nearest the fold line 6 of the flap. Thus, the opening 7 is inverted or reversed relative to a normal position, so that its base side 9 is nearest the free edge of flap 4, and substantially parallel to the plane of the side walls 1 as seen in Fig. 1. The other flap 4 is designated as a guide flap, and is provided with an opening 10 having the outline or shape of the character shown in Fig. 4. The guide flap opening 10 is defined by an elongated base edge 11 substantially parallel to the plane of the side walls 1 and a relatively shorter top edge 12 which is parallel to the base 11, and by opposite side edges defined by the upper sections 13 and the lower sections 14 thereby providing guiding means for sliding the handle member 16 into carrying position.

For reasons that will appear hereinafter, the opening 10 in the guide flap has the lower edge 11 parallel to and appreciably longer than the upper edge 12, and this relation of upper and lower, or base and top edges will prevail throughout the several modified shapes of the opening 10, including those disclosed in Figs. 4 and 7. The modification of Fig. 7 shows the provision of substantially straight side edges 15 which function as guides in the same manner as edges 14. The general shape of the modified flap opening is that of a trapezoid. The opening 10 may, however, be defined by an arrangement of edges other than those shown, so long as a portion or section of each side edge is directed at a divergent angle relative to the upper edge of the opening. It is also noted that the length of the lower edge 11 should be somewhat greater than the width of the handle end portion to receive the handle with at least a minimum clearance, and that the lengthwise trend of opening 7, as measured normal to the edge 9, should be substantially right angular to the lower edge 11 of opening 10. This limitation prevents accidental release of the handle 16 from openings 7 or 10.

The handle member 16 is substantially rectangular in outline, and in a form (Figs. 1 and 5) thereof it is provided with two opposing pairs of notches. The pivot flap engaging end of the handle is provided with lateral notches, recesses or the like, as at 17, and the relatively uniform width of the handle and tab 19 is such that it may pass through the opening 7, as shown in Fig. 6. It is noted that the width of the web

between the notches 17 is slightly less than the length of the edge 9 of opening 7. At the opposite end of handle 16, a tab 20 equal in width to that of the handle, is adapted to fit into the guide-flap opening 10, and the tab 20 is further defined by the recesses or notches 21. The depth of the notches 21 is such that the width of the web material therebetween is slightly less than the length of the upper or top edge 12 of the guide flap opening 10. Inwardly of the notches or recesses 21, the handle is provided with shoulders or guides 22 which have a divergent relation and are designed to taper gradually, as shown.

In assembling the present carrying device, the container or basket is erected and the upper marginal side wall panels 3 are folded flatwise toward the inner face of the side walls 1, the end flaps 5 (Fig. 4) being interposed. The die cut supporting flaps 4 will remain substantially upright, but can be made to assume the position as in Fig. 1 after being forced inwardly and creased at line 6. The pivot flap end 19 of the handle member 16 is inserted from the inner side through the pivot opening 7 by rotating or angling the handle until one longitudinal edge of the handle member (see Fig. 6) can be directed into the apex 8 of the pivot opening. When the tab end 19 of the handle member 16 has been inserted far enough into the pivot flap opening 7, a notch 17 will register with the apex 8 and with a rotating and swinging movement, it can be brought flatwise against the upper base 9, as shown in phantom in Fig. 6. The guide flap tab 20 of the handle member is not insertable at opening 10 in any way but flatwise to the edge 11, so long as the opposite end is located in opening 7.

After the handle recesses or notches 21 have passed through the guide opening 10, and assuming that the notches 17 properly engage the edges of opening 7, the handle is ready for use. Any lifting or upward force on the handle member 16 will cause the same to slide upwardly in the opening 10 and have a necessary pivoting relation in opening 7 to obtain an interlocked relation. Conversely when a downward force is exerted on the handle, the mutual guiding action of the tapering edges 14 (Fig. 1) of the guide hole 10 against the reversely tapering inner shoulders 22 of the guide notches, as in Fig. 5, forces the handle member flatwise against the lower edge 11 of the guide hole 10. The lower edge 11 being of slightly greater length than the greatest width of the handle member 16, the handle easily slides through the guide holes 10 into the collapsed position as in Fig. 3. During either the collapsing or erecting operations, the pivot notches 17 at all times pivot about the upper base 9 of the flap pivot hole 7. Likewise, the tapered guiding edges 22 on the handle and the side edges 13-16, or as modified at 15 in Fig. 7, of the opening 10 cooperate to effect a lowering of the handle relative to the flap when collapsing the device, or an erection of the flap upon elevation of the handle.

The basket type container of preferred construction has been above described, and we have also shown a preferred form of a closed type container in combination with the collapsible carrying device, this modification being illustrated in Fig. 8. It is pointed out that the operation of the collapsible carrying device or handle assembly employed with the modified container is identical in all respects. The structural difference between the collapsible basket and the collapsible container, as modified, resides in the

construction of handle flaps. In the basket, the flaps 4 are die cut from the upper marginal, downwardly turned side wall flaps, but in the modified form of the container, the flaps 24 and 25 are die cut from the walls of the lid 26 and the container body wall 27 respectively, and these parts of the container may be integral or separable, as desired.

The term "sliding and interlocking engagement" as used herein refers to the engagement of the handle in openings in flaps connected to the walls of a receptacle in such manner that both ends of the handle are locked in the upper part of the flap openings when the handle is grasped for lifting the receptacle, and one end of the handle slides in the lower portion of its flap opening as the carrying device is depressed to collapsed position. The term "pivoting engagement" refers to the rotation of the other end of the handle about the upper edge of the pivoting flap opening.

A further modification is shown in connection with Fig. 9, wherein one end of handle 16, as before noted in Fig. 1, is provided with the notches or recesses 17 and end tab 19 and the opposite end of the handle is provided with the notches 21 and the tapering edges 22. The present modification includes the provision of an intermediate or auxiliary set of notches 31 and tapering edges 32. The provision of the auxiliary set of notches 31 and tapering edges 32 adapts the handle as a means for locking the flaps 4 in closed position.

It is to be understood that the embodiments herein described are illustrative and not restrictive, and it is also to be understood that the invention may be susceptible of embodiment in other modified forms, and that all such modifications which are similar or equivalent hereto may come within the scope of the claims next appearing.

What we claim is:

1. In a carrying receptacle, a receptacle body blank formed from sheet material and capable of self support when erected along scored fold lines, and collapsible carrying means for the receptacle consisting of flaps extending from opposite walls of the receptacle and derived from material of those walls, each flap having an opening therein which is spaced from the flap margins, and a handle having pivot forming notches near one end for pivotal interlocked connection in one flap opening and guide notches near the opposite end for relative sliding interlocked connection in the other flap opening, said guide notches acting to direct said handle in its sliding relation in said other flap opening to a position projecting outwardly of the latter opening for permitting foldable collapse of said carrying means, and said handle having additional guide notches intermediate its ends for interlocked engagement in said other flap opening to retain the carrying means in collapsed position.

2. In a receptacle having a pair of opposed side walls with upper marginal extensions folded inwardly in flatwise relation to the inner faces thereof said side walls being connected together by a pair of opposed end walls; a carrying means comprising a pair of flaps derived from the material of the side walls approximately intermediate of their length foldably connected to the upper edges of side walls, a rectangularly shaped handle member connecting said flaps together through openings adjacent to their free outer edges, said handle member having opposed trans-

verse locking notches in each longitudinal edge adjacent to the ends thereof, providing web portions between the bases of said notches, which web portions engage and releasably interconnects the outer boundaries of said flap openings and support the weight of the receptacle in the carrying position thereof, the notches in one end of said handle being defined by parallel inner and outer right angular shoulders and the notches in the other end of said handle being defined by outer right angular shoulders and inner portions tapering outwardly from the bases of said notches, said handle between the outer shoulders thereof being of a length to dispose said connected flaps, when in the carrying position, at a predetermined angle not exceeding 90° to a horizontal plane through the fold line of said flaps, and in the retracted position for stacking said receptacle, said flaps being disposed inwardly at substantially right angles to said side walls.

3. The combination set forth in claim 2 wherein in the width of the portion of said handle member lying between the inner shoulders of the notched ends thereof is greater than the width of said openings in said flaps and said handle member is planar throughout in both the retracted and carrying positions.

4. The combination set forth in claim 2 wherein in the outer boundary of the opening in one of said flaps is parallel to the hinge line thereof and slightly longer than the width of the web portion of the first mentioned end of said handle member, said opening being shaped to permit the insertion of said first mentioned notched end of said handle member angularly therethrough, the upper boundary of the opening in the other flap being parallel to the fold line thereof, the boundaries of the sides of said opening converging from the ends of said outer boundary, the lower boundary being parallel to said outer boundary and the distance between said outer and inner boundaries being sufficient to permit the insertion of said last mentioned notched end of said handle member angularly therethrough.

5. The combination set forth in claim 2 wherein in the central portion of said handle member in retracted position is positioned below the free end edges of said flaps and the first mentioned end of said handle member releasably engages the first mentioned flap in substantially fixed longitudinal relationship, and the last mentioned end of said handle member slidably and releasably engages the other flap, whereby said handle is in substantially fixed longitudinal relationship in the carrying position and is free to slide outwardly through the opening in said flap and over the outer faces thereof to the retracted position while maintaining said releasable engaging relationship with said flap.

6. The combination set forth in claim 2 wherein in the opening in one of said flaps is of the general shape of an inverted isosceles triangle with the apex positioned toward the flap hinge and through which the first mentioned end of said handle member releasably interconnects in substantially fixed longitudinal relationship and the opening in the other flap is generally trapezoidal in shape with the longest of its parallel sides positioned nearest the flap hinge and through which the last mentioned end of said handle member is inserted, said last mentioned handle end releasably engaging with said flap in substantially fixed longitudinal relationship in the carrying position, and being slidably guided progressively through the opening in said other flap by the out-

wardly tapering portion of said handle member and the tapering side boundaries of said trapezoidal flap opening into the fully retracted position in substantially flatwise contact with the lower boundary of said opening, while maintaining said sliding relationship with said flap.

7. In an open top receptacle having a pair of opposed side walls formed with inner panels folded thereon to form the top margins of the side walls, the combination of collapsible carrying means for the open top receptacle comprising side wall flaps derived from the material of the inner panels so as to be foldable between an erect carrying position and a collapsed position directed inwardly over the open top of the receptacle, each flap being provided with an opening therethrough, and a handle member extending between said flaps for carrying the receptacle, said handle having sets of notches in its opposite end portions, one notch set being formed with inner and outer shoulders and the other notch set being formed with outer shoulders and inner tapering margins, said one notch set engaging a flap opening so that said handle is held against sliding in said opening but is free to pivot between said inner and outer shoulders relative to said flap, and the other notch set engaging the other flap opening so that said handle is free to slide through said flap opening along said tapering margins in one direction to its collapsed position and is limited in its movement in the opposite direction by said outer shoulder, so as to attain an erect receptacle carrying position.

8. The combination set forth in claim 7 wherein in each of said flap openings is provided with a rectilinear margin cooperating with said handle member in the support of the receptacle in carrying position, and the width of said handle member inwardly and outwardly of said sets of notches is uniform and greater than the length of said rectilinear margins.

9. The combination set forth in claim 7 wherein the notched end portions of said handle member enter the flap openings from the under side thereof to present a relatively smooth under surface of the flaps and handle to the contents in the receptacle when said flaps are in the collapsed position.

10. In a receptacle, the combination of a receptacle body having opposed walls, a flap integrally and foldably connected with each of said walls at a wall margin, said flaps being originally derived from the material of said body, and each thereof having an opening formed therein, one of said flap openings being in the shape of a triangle with its apex directed toward the body

wall connection of that flap and the shortest edge thereof being opposite said apex, the other flap opening being defined by two spaced and opposed parallel edges and other opposed edges which define guide edges, one of said parallel edges being equal in length to the shortest edge of said triangular shaped opening, and a receptacle carrying handle having notches in the longitudinal side margin near its opposite ends, said notches near one end being adapted to engage and pivot about the edges of said triangular opening adjacent the shortest edge thereof, and said notches near the opposite end being formed with inwardly directed divergently tapering guide edges adapted to slide along said other opposed edges of said other flap opening to displace said handle toward or from the one parallel edge thereof equal to said shortest edge of said triangular opening.

11. In a receptacle, a body blank foldably erected to form walls for the receptacle, flaps foldably connected with opposed walls of the body, one of said flaps having an opening defined by a relatively short edge which is substantially parallel with the flap fold line and in which the relatively longer edges of the opening are located between said short edge and the flap fold line, the other flap having an opening defined by a relatively short edge, an opposed relatively longer parallel edge and interconnecting edges for said parallel edges which provide guide portions, and a separate handle having pivot forming notches near one end portion and guide notches near the other end, said notched end portions being adapted to pass into said flap openings when aligned with the longest dimension of the openings and have an interlocking relation with the flaps when in engagement with the respective short edges of said flap openings, said other end of the handle having said guide notches also providing guide edges for sliding cooperation with said guide portions in said other flap to effect positive interlocking engagement and release of said handle relative to said other flap.
